UNITED STATES PATENT OFFICE.

EDWARD BRANDT AND HILIA J. BARTON, OF DETROIT, MICHIGAN.

DESIGN FOR AN ELECTRIC-LIGHTING FIXTURE.

Application filed July 6, 1925. Serial No. 14,009. Term of patent 7 years.

To all whom it may concern:

Be it known that we, EDWARD BRANDT and HILIA J. BARTON, citizens of the United States, residing at Detroit, in the county of Wayne and State of Michigan, have invented a new, original, and ornamental Design for Electric-Lighting Fixture, of which the following is a specification, reference being had to the accompanying drawing, forming part thereof.

Fig. 1 is a front elevation of an electric lighting fixture embodying our invention.

Fig. 2 is a side elevation thereof.

We claim:

The ornamental design for an electric-lighting fixture as shown.

EDWARD BRANDT.
HILIA J. BARTON.
